US0D1109708S

(12) **United States Design Patent** (10) **Patent No.:** **US D1,109,708 S**
(45) **Date of Patent:** **** Jan. 20, 2026**

(54) **RUBBER GROMMET FOR OPTICAL FIBER TERMINAL BOX**

(71) Applicant: **Accelight Technologies (Wuhan) Inc.,** Wuhan (CN)

(72) Inventor: **Hengzhi Fan**, Wuhan (CN)

(73) Assignee: **Accelight Technologies (Wuhan) Inc.,** Wuhan (CN)

(**) Term: **15 Years**

(21) Appl. No.: **29/883,786**

(22) Filed: **Feb. 3, 2023**

(30) **Foreign Application Priority Data**

Sep. 13, 2022 (CN) 202230602715.X

(51) **LOC (15) Cl.** **13-03**

(52) **U.S. Cl.**

USPC **D13/154**

(58) **Field of Classification Search**

USPC D13/123, 133, 152, 153, 154, 156, 158, D13/162, 162.1, 163, 184, 199

(57) **CLAIM**

The ornamental design for a rubber grommet for optical fiber terminal box, as shown and described.

DESCRIPTION

FIG. 1 is a front perspective view of a rubber grommet for optical fiber terminal box showing my new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof; and,

FIG. 8 is a rear perspective view thereof.

The broken lines depict portions of the rubber grommet for optical fiber terminal box that form no part of the claimed design.

1 Claim, 8 Drawing Sheets
